OTTO E. HAUSBURG, OF NEW YORK, N. Y.

WATCHMAN'S CLOCK.

1,099,439.

Specification of Letters Patent.

Patented June 9, 1914.

Application filed June 24, 1913. Serial No. 775,482.

To all whom it may concern:

Be it known that I, OTTO E. HAUSBURG, a subject of the Emperor of Germany, residing at New York, in the county of New York and State of New York, have invented certain new and useful Improvements in Watchmen's Clocks; and I do hereby declare the following to be a full, clear, and exact description of the invention, such as will 10 enable others skilled in the art to which it appertains to make and use the same, reference being had to the accompanying drawings, and to characters of reference marked thereon, which form a part of this specification.

The present invention has reference, generally to improvements in watchmen's clocks; and the same relates more particularly, to improvements in the key controlled recording mechanism of such clocks whereby the operating keys of one clock are rendered ineffectual for the operation of other clocks of the same type or style.

Watchmen's clocks of the character to 25 which my present invention relates are constructed for use by manufacturing concerns, warehouses, hotels and all kinds of institutions and large buildings in which watchmen are employed to make stated or predetermined rounds of inspection. Each clock possesses a paper-dial provided with dia- 30 grammatic divisions representing hours and portions thereof, the same being rotated by the clock-movement, and in connection with said clock is a recording mechanism for embossing or otherwise indicating upon said paper dial an identified station or location in the building. Keys for operating said recording mechanism are located at such 35 identified stations in the territory to be watched, and which it is desired that the watchman shall visit at stated intervals. The watchman carrying the clock with him proceeds upon his patrol from one station 40 to another, and takes the key at each station, inserts the same in the clock and turns the same to operate the recording mechanism, thus registering upon the paper dial the time of his visit to said station.

50 In order for the users of watchmen's clocks to obtain the lowest rates of fire and

like insurance, the clocks have to be so constructed as to comply with the demands of the National Board of Fire Underwriters, otherwise the same are not approved, and 55 their commercial value greatly depreciated. One of the most important requirements is to provide a large variety of station keys for operating the recording mechanism, so that two watchmen, each having the same 60 type of clock, cannot conspire together to have one operate both clocks and thus leave one of the patrols unprotected.

The possibility of making a variety of different shaped operating or station keys is 65 very limited, due to the necessarily peculiar shape of the key which is required to release and operate the recording mechanism, and yet some simple and easily variable means for rendering the keys of one clock ineffectual for another is highly desirable.

It is the principal object of the present invention to provide a simple, easily variable and effective means for rendering the station or operating keys of watchmen's clocks non- 75 interchangeable.

Other objects of this invention not at this time more particularly enumerated will be clearly understood from the following detailed description of the invention.

The invention consists, primarily, in the novel combination of operating key and guard device for rendering such keys non-interchangeable hereinafter more fully set forth; and, furthermore, this invention consists in the various arrangements and combinations of the several parts, all of which will be more fully described in the following specification and then finally embodied in the clauses of the claims which are appended to and which form an essential part 90 of this specification.

The invention is clearly illustrated in the accompanying drawings, in which:—

Figure 1 is a rear face view of a watchman's clock illustrating the lower portion of the casing broken away to show the recording mechanism and the station or operating key guard devices in plan; Fig. 2 is a view similar to said Fig. 1, but showing a station 100 or operating key inserted in normal position ready for manipulation to operate said re-

cording mechanism. Fig. 3 is a detail side or end view of said recording mechanism and said station or operating key guard devices. Fig. 4 is a detail cross section taken 5 on line 4—4 in said Fig. 2. Fig. 5 is a side view of a station or recording key, the bow portion being broken away; and Fig. 6 is a top edge view of the same.

Similar characters of reference are employed in all of the above described views 10 to indicate corresponding parts.

Referring now to the said drawings, the reference character 1 indicates a watchman's clock, in the casing 2 of which is mounted a 15 base-plate 3 for supporting a clock-movement and a recording mechanism. Mounted in a suitable location upon said base-plate 3 is a transversely extending vertical bracket-plate 4. Also mounted upon said base-plate 20 3, opposite to said bracket-plate 4, is a block 5, the same being provided with an opening 6 of proper shape to permit the insertion therethrough of a station or operating key. Supported between said bracket-plate 4 and 25 said block 5 is a shaft or spindle 7 upon which are pivotally mounted, side by side, a series of actuating levers 8 of a recording mechanism. Each actuating lever 8 is provided with a downwardly extending arm 9 30 at the free end of which is located the embossing die 10, each arm 9 being provided with a different character or design of embossing die corresponding with, and only operated by the operating key of, the station 35 which the same indicates. Said base-plate 3 is further provided with an opening 11 through which said arms 9 and their embossing dies 10 pass into recording contact with a paper record dial 12 supported upon 40 the opposite face of said base-plate 3, a grooved backing-block 13 being arranged to back the said paper record dial 12 against the embossing pressure of said dies 10 when said actuating levers 8 are operated.

45 The reference character 14 indicates a safety lock-bar interposed beneath the free ends of said actuating levers 8 when the same are in their normal initial position, said lock-bar only being removed when a station 50 or operating key is entirely and properly inserted in the clock, and the key turned to effect the recording operations, a suitable key actuated mechanism for removing said bar being provided, but the same not forming 55 an essential part of the present invention, and consequently not shown in detail in the drawings. Extending forwardly from said bracket-plate 4 and above said actuating levers 8 is a pivot-pin 15 upon 60 which the station or operating key is journaled when inserted operatively within the clock, the free end of said pivot-pin extending through the key passage or opening 6 of said block 5. Connected with said casing

2, so as to be located opposite said block 5 65 is a ward-block 16, the same having a key- 70 passage or opening 17 registering with said key-passage or opening 6 of the block 5, and corresponding to the end configuration of the operating or station keys. Connected by 75 one end with said bracket-plate 4 and extending transversely across and above said actuating levers 8 so as to be connected by its other end to one side of said block 5 is a bridge-piece 18, the same being provided 80 with a longitudinally disposed series of perforations 19 in any one of which may be selectively supported a ward-stud or pin 20. Said ward-stud or pin 20 may be externally threaded, and said perforations 19 may be 85 internally threaded for the reception of said ward-stud or pin 20, and thus provide means for rigidly fixing the same in the desired position in supported relation to said bridge-piece 18.

85 The reference-character 21 indicates the bow of a station or operating key, from the said bow of which extends a tubular stem 22 which is adapted to telescope over said pivot-pin 15 when said key is inserted in the 90 clock. Extending outwardly from one side of said stem 22, adjacent to its free end, is the bit-plate 23 of said key which may be provided with suitable gatings 24 corresponding to ward-points of the key-guard mechanism. Extending longitudinally of said bit-plate 23 at its outer marginal edge and projecting upwardly from the surface of said bit-plate 23 is a shoulder 25, the upper surface of which is preferably chamfered or inclined downwardly from its inner longitudinal edge to its outer longitudinal edge. Suitably located in connection with said shoulder 25 is a lug 26 upon the upper surface of which is a pressing-stud 27. When 100 said key is turned its bit-plate 23 carries around said shoulder 25 with the lug 26 and pressing-stud 27 bringing the latter into operating contact with the free end of one of said actuating levers 8 thereby pressing 110 downwardly the latter to carry its arm 9 and die 10 into recording contact with said record-dial 12. Of course, it will be understood that the number of station or operating keys correspond to the number of actuating-levers 8, and consequently each key is arranged to operate one of said actuating levers only, and will not serve to operate any of its fellows, this result being accomplished by positioning upon the shoulder of 115 the bit-plate of each key a lug 26 and pressing stud 27 corresponding in registration, when the key is inserted in the clock, to the actuating lever 8 desired to be operated. Extending outwardly from the longitudinal 120 free edge of said bit-plate 23, and projecting therefrom in the same plane as said bit-plate is a guard-lip or shoulder 28. When 125

the said key is inserted in the clock said guard-lip or shoulder 28 extends beneath said ward-stud or pin 20, and since the operating movement of the key must carry the 5 bit-plate 23 upward and over in a revolving movement about said pivot-pin 15, said guard-lip or shoulder 28 by engaging said ward-stud or pin 20 prevents such operative movement of the key unless the said 10 guard-lip or shoulder 28 is provided with a gating 29 which registers beneath said ward-stud or pin 20 when the key is completely and fully inserted within the clock, so as to permit said ward-stud or pin 20 to 15 pass therethrough and consequently said guard-lip or shoulder 28 to pass by the said ward-stud or pin 20.

If the watchman's clock is provided with a recording mechanism adapted to register 20 the patrol of sixteen stations, there will, of course, be sixteen station or operating keys, each accommodated with operating means for operating one of the sixteen actuating levers 8, as above described, but each of the 25 sixteen keys will be provided with said guard-lip or shoulder 28 having the same location of the gating 29 therein which will correspond to the position of the ward-stud or pin 20 as located upon the bridge-piece 18, and consequently the set of station or 30 operating keys is thus constructed to operate only its companion clock. In another clock of the same type the said ward-stud or pin 20 is changed with relation to its position on the bridge-piece 18, by fixing said 35 ward-stud or pin 20 in another of the series of perforations 19. This being done, it follows that the set of keys of the first clock will not operate the second, since the gating 40 29 of the guard-lip or shoulder 28 of said keys will not register with the changed position of said ward-stud or pin 20 in the second clock, and consequently the guard-lip or shoulder 28 of such keys will, by engaging 45 said ward-stud or pin 20, obstruct the revolving or operative movement of the keys in the second clock. It will thus be understood that by changing the position of the said ward-stud or pin 20 in a series of 50 clocks, and the gating 29 of the guard-lip or shoulder 28 of a corresponding series of station or operating keys, the keys designed for use in one clock are thus rendered inoperative as to the other clocks; in other words, 55 the several sets of keys are noninterchangeable.

It will be clearly evident that such an arrangement and construction of key controlled mechanism and operating keys, as 60 above described, is highly desirable under various conditions of use to which watchmen's clocks are put; for example, where there are more than one watchman in a single institution each having a separate patrol

or beat, since neither one can operate the 65 clocks of any of his fellows and thus permit the latter to shirk his duties.

I am aware that some changes may be made in the general arrangements and combinations of the several devices and parts, as 70 well as in the details of the construction of the same, without departing from the scope of the present invention as set forth in the foregoing specification. Hence, I do not limit my present invention to the exact arrangements and combinations of the various 75 devices and parts as described in the said specification, nor do I confine myself to the exact arrangements or details of the construction of the said parts as illustrated in 80 the accompanying drawings, except as limited by the scope of the appended claims.

I claim:

1. In a watchman's clock the combination with a key controlled recording mechanism 85 of a series of station keys, a bridge-piece supported in connection with said recording mechanism, a ward-stud supported by said bridge-piece, said ward-stud being adapted to be shifted to different positions upon said 90 bridge-piece, each station key having a bit-plate provided with a longitudinal shoulder carrying means for operating said recording mechanism, said shoulder extending over said ward-stud so as to prevent turning the 95 key in the wrong direction the bit-plate of each station key having a guard-lip adapted to extend beneath said ward-stud when said keys are inserted in their initial position for operating said recording mechanism, and said 100 guard-lip of each key having a gating therein adapted to register with said ward-stud when said keys are inserted in their initial position for operating said recording mechanism. 105

2. In a watchman's clock the combination with a key-controlled recording mechanism of a series of station keys provided with tubular stems, a pivot-pin extending in a fixed relation above said recording mechanism for 110 the reception of the tubular stems of said station keys, each station key having a bit-plate extending outwardly from said tubular stem and provided with a longitudinal shoulder carrying means for operating said 115 recording mechanism when said keys are turned upon said pivot-pin, a fixed bridge-piece paralleling said pivot-pin, a ward-stud projecting from said bridge-piece, means for securing said ward-stud in different positions upon said bridge-piece, said longitudinal shoulder of said bit-plate extending over said ward-stud so as to prevent turning the 120 key in the wrong direction, the bit-plate of each station key having a guard-lip projecting from its free longitudinal edge, the same extending beneath said ward-stud so that the latter projects into the path of the revolving 125

movement of said bit-plate and said guard-lip, and said guard-lip of each key having a gating therein adapted to register with said ward-stud when said keys are completely inserted in their initial position for operating said recording mechanism.

In testimony, that I claim the invention

set forth above I have hereunto set my hand
this 20th day of June, 1913.

OTTO E. HAUSBURG.
